Max Simon, Oak Park, Ill., assignor to Chicago Sample & Sanitary Menu Cover Co., Chicago, Ill., a corporation of Illinois

Application May 26, 1937, Serial No. 69,562

Term of patent 7 years

To all whom it may concern:

Be it known that I, Max Simon, a citizen of the United States, residing at Oak Park, in the county of Cook and State of Illinois, have invented a new, original, and ornamental Design for a Menu Holder or Similar Article, of which the following is a specification, reference being had to the accompanying drawing, forming a part thereof.

Figure 1 is a perspective view of the menu holder showing my new design;

Figure 2 is a front elevational view; and

Figure 3 is an end elevational view thereof.

The dominant features of the design reside in the oppositely and angularly disposed advertising panels, bounded at the ends by an arcuately contoured stepped formation forming a support for an elongated channel-shaped menu supporting clip, as shown.

I claim:

The ornamental design for a menu holder or similar article substantially as shown and described.

MAX SIMON.
